US00D963255S

(12) **United States Design Patent** (10) Patent No.: **US D963,255 S**
Chen (45) Date of Patent: ** Sep. 6, 2022

(54) **PET FEEDER**

(71) Applicant: **Zhujun Chen**, Guangdong (CN)

(72) Inventor: **Zhujun Chen**, Guangdong (CN)

(73) Assignee: **Shenzhen Gaodi Digital Co., Ltd.**,
Guangdong (CN)

(**) Term: **15 Years**

(21) Appl. No.: **29/757,316**

(22) Filed: **Nov. 5, 2020**

(51) LOC (13) Cl. **30-07**

(52) U.S. Cl.

USPC **D30/122**

(58) **Field of Classification Search**

CLAIM

The ornamental design for a pet feeder, as shown and described.

DESCRIPTION

FIG. 1 is a rear and bottom perspective view of a pet feeder showing my new design;

FIG. 2 is a front and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 8 Drawing Sheets
